UNITED STATES PATENT OFFICE.

WILLIAM C. COZAD, OF CHICAGO, ILLINOIS, ASSIGNOR OF ONE-HALF TO ARTHUR T. MOLONEY, OF CHICAGO, ILLINOIS.

TELEGRAPH SENDING-MACHINE.

1,304,025.

Specification of Letters Patent. Patented May 20, 1919.

Application filed February 12, 1918. Serial No. 216,702.

To all whom it may concern:

Be it known that I, WILLIAM C. COZAD, a citizen of the United States, residing at Chicago, in the county of Cook and State of Illinois, have invented new and useful Improvements in Telegraph Sending-Machines, of which the following is a specification.

This invention relates to telegraph sending instruments having a vibrating element 10 for producing a plurality of dot or dash impulses through the line, and the object of the invention is to provide a novel and improved contact for the vibrating element designed to eliminate indistinctness in the message at the receiving end of the line.

The object stated is attained by means of a combination and arrangement of parts to be hereinafter described and claimed, and in order that the same may be better understood, reference is had to the accompanying drawing, forming a part of this specification.

In the drawing,

Figure 1 is a perspective view of a fragment of the instrument showing the application of the invention, and

Fig. 2 is an enlarged section on the line 2—2.

Referring specifically to the drawing 5 denotes the base of the instrument above 30 which is located a horizontally vibratory member in the form of a rod 6 having a resilient shank 7 and a handle 8, and also carrying a contact block 9. One end of the rod 6 is adjacent to an abutment 10 and carries a ballast 11.

Opposite the contact block 9 is a post 12 through which is threaded a screw 13. To the outer end of this screw is made fast a small coil spring 14 which projects from the 40 screw and has its outer end provided with a platinum contact stud 15. This stud is opposite the vibratory contact block 9 and is engageable thereby when said block swings

back and forth as the rod 6 vibrates, whereby the circuit is made and broken. The circuit connections have not been illustrated as they form no part of the present invention.

To shield the stationary contact member composed of the parts 14 and 15 from injury, a tube or sleeve 16 is screwed on the shank 50 of the screw 13, said sleeve forming a housing for the spring 14, but leaving the contact 15 exposed.

It will be seen from the foregoing that the vibratory contact member 9 is rigid, and the 55 stationary contact member 15 is yieldable when struck by the former. As usually constructed, the vibrating member carries a yieldable contact and the stationary contact is rigid. With this structure a lag is very 60 often experienced, causing the dot and dash impulses to blend and to appear indistinct and unintelligible at the receiving end of the line. However by the present arrangement of a yieldable stationary contact on a 65 rigid support, and opposite a rigid vibratory contact, no lag is experienced and the impulses are clear and distinct.

The device is very simple and inexpensive and can be applied to existing instruments 70 without any changes or alterations, it being necessary only to fit the screw 13 with the parts 14, 15 and 16.

I claim:

In a telegraph sending machine, a vibratory member having a rigid contact, a contact engageable by said rigid contact, a support, a screw carried by the support, a spring carried by the screw and projecting therefrom, the second-mentioned contact being 80 carried by the outer end of the spring and a sleeve carried by the screw and housing the spring, the last-mentioned contact projecting from the sleeve.

In testimony whereof I affix my signature. 85
WILLIAM C. COZAD.
